UNITED STATES PATENT OFFICE

168,802

MELTED BUTTER DISPENSER

Frederick H. Newman, Jr., Port Washington, and Clifford Brooks Stevens, Milwaukee, Wis., assignors to Superdisplay Incorporated, Milwaukee, Wis., a corporation of Wisconsin

Application September 29, 1952, Serial No. 21,634

Term of patent 14 years

(Cl. D2—3)

To all whom it may concern:

Be it known that we, Frederick H. Newman, Jr., a citizen of the United States, and resident of Port Washington, county of Milwaukee, and State of Wisconsin, and Clifford Brooks Stevens, a citizen of the United States and a resident of Milwaukee, in the county of Milwaukee, State of Wisconsin, have invented a new, original, and ornamental Design for a Melted Butter Dispenser, of which the following is a specification, reference being had to the accompanying drawings, forming part thereof.

Fig. 1 is a perspective view looking principally at one side and the front of a melted butter dispenser embodying our new design;

Fig. 2 is a perspective view looking principally at the rear of the melted butter dispenser.

The side which is opposite to the side shown in

Fig. 1 has the same appearance. The characteristic features of our design reside in the portions shown by means of full lines in the drawings.

We claim:

The ornamental design for a melted butter dispenser, substantially as shown and described.

FREDERICK H. NEWMAN, JR.
CLIFFORD BROOKS STEVENS.
